(57) **CLAIM**

The ornamental design for an ice tray, as shown and described.

DESCRIPTION

FIG. 1 is a front elevation view of an ice tray showing my design;

FIG. 2 is a back elevation view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is an exploded view thereof.

The dashed or broken lines shown in the drawings depict portions of the ice tray in which the design is embodied that form no part of the claimed design.

1 Claim, 9 Drawing Sheets
